UNITED STATES PATENT OFFICE.

ARTHUR SELIGMANN, OF BREMEN, GERMANY.

METHOD FOR LOW-TEMPERATURE COOLING, LIQUEFACTION, AND SEPARATION
OF GASES.

Application filed March 3, 1924, Serial No. 696,596, and in Germany May 26, 1922.

My invention relates to a method for low temperature cooling, and for liquefaction and separation of gases and to an apparatus for carrying out the method.

5 In order to liquefy a gas heat has to be withdrawn from it. If the liquefaction is not the final purpose but merely a means for the separation of a gas mixture into its constituents, if therefore, otherwise expressed, 10 the gases may vaporize again so that they may absorb again the heat which had been withdrawn, a counter-current heat exchanger known per se is used. In this case it is merely necessary to compensate, besides for 15 the expenditure in energy caused by the reduction of entropy at the separation, only for the losses of cold of the apparatus. This compensation of the losses of cold is generally carried out by sending the gases under 20 high pressure into the apparatus to let them flow out expanded. The heat content of the gases is less great under pressure so that in this manner, when the gases are brought again by means of the counter current 25 heat exchanger to the temperature of the inflowing gases, permanently more energy is taken from the apparatus than sent into the same and this difference produces a cooling of the entire system until the losses 30 by absorption of radiant heat have become equal to the energy difference between the inflowing and the outflowing gases. So simple is this kind of cooling, however it presents the grave inconvenience that the gas 35 is compressed to high pressure and that for this reason much valuable energy has to be spent. Very high pressure (in practice generally 200 kg/cm²) has to be applied especially at the starting of the apparatus when 40 all the metal and insulating masses of the same have to be cooled. Numerous experiments for improvement have already been made which however had all for their object to withdraw energy from the apparatus 45 in any other less expensive manner. Expansion machines are used for this purpose which transmit the mechanical work to the outside but as such machines, in order to be effective, have to work at very low temperatures they present considerable difficulties of service and have not been generally adopted. The cooling by means of ammonia 50 machines comes also under this head but the

technical heating effect of the same is very limited, the working of the machine being 55 further expansive and complicated.

It might however be useful to load the gases which flow out of the apparatus with any other form of energy as heat and to let the same flow out of the apparatus at this 60 state, viz. with great velocity. The question is merely, how much energy is withdrawn from the apparatus, that is to say which is the sum of the kinetic energy of the outflowing gases plus their heat contents. From 65 this point of view it serves no purpose to produce the high outflow velocity directly at the outlet branch of the counter current apparatus (for instance in a nozzle) as in this case the gases would escape at cold 70 state, viz. with low heat contents. The velocity must be produced already so far down in the apparatus that the outflowing gases have still the opportunity to re-heat themselves in counter current up to approximately 75 the temperature of the inflowing gases. The great velocity must therefore be maintained over long distances in opposition to the pipe friction. It is obvious that for this purpose a considerable decrease of pressure must be still at disposal for the return 80 travel of the gas and owing to this condition the idea which is good and known per se has never been practically utilized for the liquefying of air. As the liquefying of air 85 serves at the present times particularly for the purpose of the production of oxygen it is rather difficult to work under increased pressure a separation apparatus (column) 90 which fulfills the modern requirements.

My invention differs from the above mentioned idea in that I abandon the high outflow velocity in the state of inertia and utilize the same merely for the starting of the apparatus. The following example is intended to explain the idea of the invention:

The commonly used working method consists in starting at a pressure of 200 kg/cm² and in expanding in the throttle valve to approximately atmospheric pressure. In 100 this case the refrigerating efficiency is 8.5 kcal/kg compressed air, supposed that the cooling water has a temperature of 17° C. If with the aid of this refrigerating duty the apparatus had been cooled and a sufficient quantity of liquid air had been pro-

duced for the rectification, the pressure in the compressor was reduced, by opening the throttle valve further so that only the losses by adsorption of radiant heat were covered, 5 approximately to 70 kg/cm² so that the refrigerating efficiency amounted still to 3.5 kcal/kg. According to my improved method however the working is as follows:—At the state of inertia I compress as hitherto the air 10 to 70 kg/cm², I make the same expand in the throttle valve to approximately atmospheric pressure and send the same at this state through the column and make the separated constituents flow out through the counter current apparatus. 15 At the starting I do not however expand at the throttle valve so far as stated but only to about 30 kg/cm² and I use this pressure to force the air in outward direction with a very great velocity. 20 When the outflow velocity amounts to only about 250 m/sec. (in turbines and blowers much higher velocities occur) each kilogram of air draws along 7.5 kcal of kinetic energy so that the total refrigerating efficiency 25 amounts in this case to $3.5 + 7.5 = 11.0$ kcal/kg or to 30% more than according to the commonly used methods.

If however the velocity in the end part of the counter current apparatus has to be 30 greater at the starting than at the state of inertia either the quantity of gas which flows through must be greater or the free cross section must be made narrower.

I have therefore the possibility to increase 35 the quantity of the air for the purpose of starting (instead as hitherto the pressure). It may therefore become necessary to increase the number of revolutions of the compressor or to work with several compressors for one apparatus, but in most cases it will be impossible to regulate the quantity, 40 which flows through, in such a degree as it would be necessary but this kind of regulating might, under certain conditions be useful for the second manner of working according to the invention, which will be discussed later on. According to the invention 45 the cross section for the outflowing gas is narrowed at the starting. The return conduit for the gases in the counter current is composed of several tube-lengths of which only one or several are used for the starting, the other ones being shut off. This method 50 presents the inconvenience that the heat exchanging surface is smaller at the starting and in order to avoid this inconvenience I construct the counter current apparatus in such a manner that the return conduit for 55 the gases is composed of several pipes which, at the state of inertia are connected in parallel and for the starting in series; or I interchange, for the purpose of the starting, the inflow pipe and the return pipe in the counter current apparatus in such a manner 60 that the high pressure air flows through the valve f' where it expands to about 1.3

wide supply conduit expanded gases flow through the narrow high pressure tubes. If for instance in the example given above the velocity of the high pressure air at the state of inertia is supposed to be 3.5 m/sec. the 70 outflowing air would have to adopt at the starting an outflow velocity of 245 m/sec. If the air were free to move through the apparatus in inverse direction the column ought to have walls of sufficient thickness to 75 support a pressure of 30 kg/cm²; besides the high manufacturing cost this would mean a considerable increase of the metal mass and consequently a much longer starting time. In order to avoid this inconvenience I can 80 disconnect the column from the main current and use the counter current apparatus merely air liquefying machine, the liquid produced being allowed to trickle off through the column siphon after it has expanded, the 85 column being cooled at the same time.

The advantages of my new method reside in the following:—Less energy is consumed during the starting; according to the above cited example about 20% less than usual. 90 This plays however, in comparison with the total consumption of energy of the plant, not an important part and what is much more important is that the cooling efficiency at the starting becomes greater and 95 that the starting time is consequently shortened, according to the example given of about 30%. The main thing is however the absolute avoiding of the high starting pressure. Always the same end pressure of the compressor, for instance 70 kg/cm² is used. As all the different apparatus (separation apparatus, drying battery) pipe conduits, flanges, screws and the like must be calculated always for the highest pressure which 100 could possibly occur, it is evident that a saving of expenses as well as a great simplification of the construction of the compressor may be realized. To this is further added 105 that the driving motor for the air compressor had to be dimensioned hitherto according to the efficiency at the starting so that it was loaded at the state of inertia with only 80%. According to the improved 110 method it runs always with equal efficiency 115 so that it can be considerably smaller and is much cheaper and adapted to work with its nominal efficiency, viz. with the most favorable degree of efficiency.

A form of construction of an apparatus 120 adapted for carrying out the improved method is diagrammatically shown in Fig. 1 of the drawing.

A is the counter-current heat exchanging 125 apparatus, B the column.

During the state of inertia the air flows through the valve a with approximately 70 kg/cm² and through the high pressure air conduit a' and the evaporator coil f to the 130 valve f' where it expands to about 1.3

- kg/cm² abs. and is delivered on the top of the column B. The nitrogen flows into the atmosphere through the valve *g*, the counter current heat exchange A and the valve *e*.
 5 The oxygen flows out from the bottom part of the evaporator through the heat exchanger and through the valve *d*. The valves *b*, *c*, *h* and *i* are closed.
- At the starting the air flows at approximately 10 70 kg/cm² through the valve *b* and the counter current heat exchanger A to be expanded in the valve *h* to approximately 30 kg/cm², returns to the heat exchanger into the narrow high pressure tubes and 15 flows out at great velocity through the valve *c*. As soon as liquid has been produced it is expanded by the valve *i* to approximately 1 kg/cm² abs. and it flows out through the column and through the oxygen tubes *d*.
 20 The valves *a*, *e*, *f'* and *g* are closed.
- This invention relates further to a method 25 for low temperature cooling, liquefaction and separation of gases in which only one of the constituents separated is expanded and flows out from the counter current apparatus with great velocity, the other constituent flowing out at a pressure above-atmospheric and with moderate velocity. This part of the invention is to be applied 30 principally to the separation of mixtures containing hydrogen or helium, especially water gas. The hydrogen or the helium leaving the separation device slowly and under pressure, the more heavy constituent, especially the carbonic oxide, leaving the separation apparatus at great velocity and expanded. The advantage of this measure 35 consists mainly in the fact that mixtures which contain more than 30% of hydrogen and separated while hitherto one had to proceed in a very complicated manner by re- 40
- turning part of the carbonic oxide produced to the gas mixture to be separated.
- A form of construction of an arrangement for carrying out this part of my invention is shown in Fig. 2 of the drawing. 45
- The gas mixture is admitted into the counter current apparatus A through the tube *l* to be separated in the separation apparatus B. The carbonic oxide leaves the counter current apparatus through the narrow tube *n* expanded and at great velocity, the helium or the hydrogen leaving the counter current apparatus through the wider tube *m* slowly and under pressure. 50
- What I claim is:
1. A method of low temperature cooling, liquefaction and separation of gases, which consists in causing the gases to flow through a countercurrent heat exchanging apparatus and to increase the rate of speed upon starting the process beyond the rate of speed of the flow maintained during the normal performance of the process. 55
  2. A method of low temperature cooling, liquefaction and separation of gases, which consists in causing the gases to flow through a countercurrent heat exchanging apparatus, increasing upon starting of the process 60 the rate of speed at which the gases leave the countercurrent heat exchanging apparatus beyond that rate of speed which is maintained during the normal performance of the process, and causing upon starting the 65 process at reduced temperature of the countercurrent heat exchanging apparatus to flow in a larger volume through the apparatus than during the normal performance of the process. 70
- In testimony whereof, I affix my signature. 75

ARTHUR SELIGMANN.
